(57) **CLAIM**

We claim the ornamental design for a sediment filter attachment for nozzle, as shown and described.

DESCRIPTION

FIG. 1 is a perspective view of a sediment filter attachment for nozzle showing our new design;

FIG. 2 is a side elevational view thereof, the elevational view of the opposing side being identical thereto;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a reduced side elevational view showing the sediment filter attachment for nozzle in use; the broken lines depict environmental structure for illustrative purposes only and form no part of the claimed design.
